CLAIM

The ornamental design for a wheelbarrow as shown and described.

DESCRIPTION

FIG. 1 is a front, right and top perspective view of a wheelbarrow showing our new design;

FIG. 2 is a rear, left and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the drawings illustrate portions of the wheelbarrow which form no part of the claimed design.

The battery housing cover is transparent or translucent.
